UNITED STATES PATENT OFFICE.

FREDERICK R. SEIDENSTICKER, OF MERIDEN, CONNECTICUT, ASSIGNOR TO
ELI BIRDSEY AND WALLACE MILES, OF SAME PLACE.

DESIGN FOR PEN-RACK STANDARD.

Specification forming part of Design No. 7,191, dated February 17, 1874; application filed October 11, 1873.
[Term of Patent 3½ years]

To all whom it may concern:

Be it known that I, FREDK. R. SEIDENSTICKER, of Meriden, in the county of New Haven and State of Connecticut, have invented a Design for Standard for Pen-Racks, of which the following is a specification:

The nature of my design is fully represented in the accompanying photographic illustration, to which reference is made.

What I desire to be secured as my invention is the form and configuration of the standard, and the lines and figures of ornament thereon, as shown in the illustration.

I am aware that the manner of connecting these standards is not new, and I do not claim it. The distinctive character of my design is the configuration of the standard.

What I claim as my invention is—

A design for a standard for pen-racks, as shown by accompanying photograph.

FREDERICK R. SEIDENSTICKER.
